UNITED STATES PATENT OFFICE.

FRANKLIN G. BEACH, OF CHICAGO, ILLINOIS.

TELEPHONE-EXCHANGE APPARATUS.

SPECIFICATION forming part of Letters Patent No. 405,867, dated June 25, 1889.

Application filed December 8, 1887. Serial No. 257,309. (No model.)

To all whom it may concern:

Be it known that I, FRANKLIN G. BEACH, a citizen of the United States, residing at Chicago, in the county of Cook and State of Illinois, have invented a certain new and useful Improvement in Telephone - Exchange Apparatus, (Case 5,) of which the following is a full, clear, concise, and exact description, reference being had to the accompanying drawings, forming a part of this specification.

My invention relates to telephone-exchange apparatus, and more especially to that system of telephonic communication known as the "multiple-switch-board system." As is well known, in multiple-switch-board systems separate boards are provided, each board being furnished with a separate switch or terminal for each of the telephone-lines of the exchange. These boards are preferably placed end to end, so as to form one continuous line of switch-boards. These boards, when once placed in line, are sometimes spoken of collectively as the multiple switch-board, while the different duplicate portions thereof are termed "sections" of the multiple switch-board. I shall, however, in this description speak of the duplicate sections as different switch-boards. The object of duplicating the boards is to facilitate the operation of large exchanges. The cables necessary to carry the wires are arranged at the rear of the board and connected with the different parts of the spring-jack switches. The spring-jack switches have heretofore been built up in strips which strips have been inserted from the rear of the board. After the wires are connected with the spring-jack switches it has been quite difficult to get at the spring-jacks to make repairs when required.

In all multiple-switch-board systems of telephone-exchange it is essential that a test be provided to indicate to the operator at any board whether a given line is or is not busy at one of the other boards. This test is usually accomplished in the systems heretofore devised by the making of a contact or cross by the plug when inserted in a spring-jack, such contact or cross being between the test-circuit and the main-line circuit. The test-circuit is normally open, and hence when thus crossed with its main line is provided

with one ground. When a telephone or other circuit-indicating device is connected with this same test-circuit upon another board, the test-circuit will be completed through a telephonic or other circuit-indicating device. In all such systems the cross or connection of the main line with the test-circuit is maintained during the entire time talking is going on. This has the effect to greatly increase the electro-static capacity of the talking-circuit, thereby reducing the margin for practical talking over a given circuit and adding to the "cross-talk" from and to other circuits which may be in use simultaneously.

One of the essential advantages of my invention over other multiple-switch-board systems is that when the test shall have been made and the plug inserted the test-circuit is closed directly to ground without contact or crossing between the test-wire and the main circuit during the time any given line may be used for talking. The test-circuit being closed directly to ground will contain less resistance than when grounded through the medium of the main line, and the test will be more positive and the danger of false tests arising from high static capacity is obviated. This trouble from cross-talk caused by the high static capacity of the test-wires when crossed with their telephone-lines has heretofore been a very serious obstacle to the satisfactory working of multiple-switch-board systems, not only on account of the confusion necessarily caused by the cross-talk, as above stated, but also on account of the capacity of the test-wires, since where the test-wires have been quite long, a busy test has been falsely indicated when the test-wire was not actually crossed with its telephone-line.

In my application, Serial No. 254,029, filed November 2, 1887, I have shown a system of telephone-exchange in which the subscribers are arranged in pairs, so that the line of either one of the pair may be utilized as one side of a metallic circuit. The two single lines of any pair may be thus united to form a metallic circuit between either of a pair of stations and the central office.

My invention herein, in respect to the test-circuits, while designed more especially for such a system of metallic circuits, may be

used in any system of metallic circuits or in a single-line system of multiple switch-boards and also in combined systems having part of the lines single and part metallic. My improvement in the spring-jack switches, as will be readily understood, may be used in any system to which they are adapted.

Heretofore various test-circuits and different forms of spring-jack switches have been employed. As to the prior state of the art, reference is made to the following United States Letters Patent: No. 308,315, granted Milo Kellogg November 18, 1884, No. 356,425, granted Charles E. Scribner January 18, 1887, and No. 374,908, granted Charles E. Scribner December 13, 1887, application filed May 12, 1885.

In the practical working of telephone-exchanges it is important that the apparatus, and especially the spring-jack switches, be readily accessible for inspection or repairs.

The objects of my invention are, briefly stated, as follows: First, to provide spring-jack switches capable of doing the work required which will occupy the least possible space upon the boards; second, to provide a local test-circuit suitable more especially for metallic circuits, whereby troubles heretofore existing on account of crossing the test-wires with the telephone-lines and from the static capacity of the test-wires are obviated, and, third, my invention consists in certain details of construction and special circuit-connections hereinafter described and claimed.

My invention will be readily understood by reference to the accompanying drawings, in which—

Figure 1, Sheet 1, is a front elevation of a strip of ten spring-jacks embodying my invention. Fig. 2 is a detailed sectional view of one of the spring-jacks on line $x x$ of Fig. 1. Fig. 3 is a rear perspective view showing the front portion of three spring-jacks removed. Fig. 4 is a detailed sectional view of a spring-jack, showing a loop-plug inserted therein. Fig. 5 is a plan showing several spring-jacks of a strip. Fig. 6 is a view from below of the same. Fig. 7 is a front view showing the contacts of the switches, the front or removable portion of the strips having been removed. Fig. 8 is a detailed view showing a modification of the contacts provided upon the tube or metallic socket. Fig. 9, Sheet 2, is a diagram illustrative of two metallic circuits and their test-wires connected with my spring-jack switches upon two multiple switch-boards and operator's apparatus at the different boards for receiving the calls and making the tests and connections and transmitting the signals to the subscribers' stations. Fig. 10, Sheet 3, shows a single-line connection with a metallic circuit. Fig. 11 is a modified form of the spring-jack switch, in which the thimble or metallic socket is in two parts which are insulated from one another. The front portion serves as the test-piece. Fig. 12 is a sectional

view of another modification of the spring-jack switch, in which the test-spring is permanently connected with a separate test-piece at the front. Fig. 13 is a sectional view showing a hole bored through the rubber frame of the switch, through which the wire which connects the test-spring with the test-plate is preferably run.

I will first describe my spring-jack switch as illustrated on Figs. 1 to 8 of the drawings. In Fig. I have shown a strip of ten switches, and adjoining at opposite ends portions of two other strips. These spring-jacks are built up upon rubber frames, the frames or rubber portion of each strip consisting of the front removable portion a , which carries the metallic socket a' , and the rear portion b , on which are mounted the different springs of the spring-jacks. It will be observed that the sockets a' are each provided with contact-points a^2 and a^3 . These points are preferably of the form shown in Fig. 8, the horizontal extensions from the socket being preferably perforated, as indicated at a^4 , the perforations being bored out, preferably tapering upwardly, so as to permit any dust that might accumulate to work out away from the contact-points without clogging. The portion a may be secured to the portion b by means of screws or in any other suitable manner, so as to permit the front portion to be readily removed to make the points of the switches accessible, as shown in Fig. 7.

Each spring-jack I have provided with a line-terminal spring c' , a corresponding insulated contact c^2 , the spring c^3 , with which the outgoing limb of a metallic circuit may be connected, and the spring c^4 , with which the test-wire may be connected, and under the test-springs I provide a ground-connection c^5 . The springs c' and c^3 and c^4 are insulated from one another, and are so adjusted as to press normally inwardly. Between springs c' and c^3 , I preferably place flexible rubber or other insulating material, as shown in Figs. 2 and 6. The contact c^2 is bored out, so as to admit a loose non-conducting pin c^6 . The line-spring c' , re-enforced by spring c^3 , having a greater strength than the test-wire spring c^4 , will hold the said spring c^4 up in contact with contact a^2 of the socket a' , as shown in Fig. 2. The pin c^6 being forced up permits the spring c' to close upon its normal contact c^2 , as shown. When a loop-plug is inserted in a spring-jack switch, as shown in Fig. 4, spring c' will be separated from its normal contact c^2 and closed to the tip of the plug. The force of spring c' having been removed from the pin c^6 , spring c^4 will separate from its normal contact with the socket and close upon the ground-strip c^5 .

It will be observed that the spring c^3 of a line-out is adjusted so as to normally press inwardly toward spring c' , the rubber stud c^7 , between the springs c^3 and c' , however, keeping their free and movable-ends insulated. When spring c' is separated from its

contact by the insertion of the plug, it is at the same time forced against the stud c^7 , and this moves spring c^3 to close upon the point a^3 of the socket a' . Thus as spring c^3 is disconnected from the socket spring c^3 is closed thereon, as shown in Fig. 4. The plug being inserted in the socket, the metal sleeve of the plug will be closed to the socket, and hence to the spring c^3 . On removing the plug the 10 springs will resume the position shown in Fig. 2. When in this position, if the tip of a plug be touched to the socket a' , connection will be made between the tip and the test-spring. The socket a' upon the face of 15 the board is thus made to answer a double purpose. The object of these different connections and the advantage of making the front portion a removable will be more fully understood in connection with the description 20 of the circuits.

In Fig. 9 the circuit of line-in d may be traced through a line-spring and its contact-point of a switch on each of the boards, and from the contact-point of the switch on the 25 last board through the listening-in spring-jack d' of the line. Continuing then from the listening-in spring-jack, this circuit may be traced through the individual annunciator d^2 of the line to the spring-lever of the 30 grounding-switch. A loop-plug being inserted in this switch, the spring d^3 is closed to the tip of the plug and also to the contact d^4 . From this contact d^4 the circuit may be traced normally by wire d^5 to ground contact-spring 35 d^6 . Thus a signal sent in over line d will pass over said line d , as traced through the switches on the different boards, the annunciator d^2 to spring d^3 of the grounding spring-jack, and thence by contact d^4 and wire d^5 to 40 ground-spring d^6 . Sending current to throw down shutter d^2 is the first step in making a connection. The operator at board 1, seeing the shutter fall, at once loops her telephone into the circuit of the calling subscriber's 45 line. I have for clearness shown a simple form of cam-lever loop-key for doing this work.

The operator, by simply throwing up cam-lever e to the position shown, loops the telephone into the circuit of the line, and at the 50 same time disconnects wire d^5 from the ground-key d^6 and closes said ground-key to the contact e' of the test-wire of the calling-line d . The test-wire circuit I will describe in 55 detail later. The operator thus, on seeing a shutter fall, throws up the cam-lever, and this brings her telephone into the circuit of the line, at the same time putting on the busy test.

60 I will now trace the circuit thus formed through the operator's telephone. Beginning at spring d^3 of the grounding spring-jack, the circuit will pass through the tip of the loop-plug, and thence by a strand f' of the cord to a 65 contact f^2 of the loop-key, and thence by the wire f^3 to calling-key f^4 , and thence by wire f^5 , through the telephone f^6 , and by wire f^7 to the

other calling-key f^8 , and thence by wire f^9 to contact f^{10} of the loop-key, with which the other strand f^{11} of the cord of loop-plug f is connected, this other strand f^{11} being connected with the sleeve f^{12} of the loop-plug, as shown more clearly in Fig. 4. I have thus traced the circuit from the tip of plug f through the operator's telephone f^6 and back to the sleeve 70 of the plug. I have heretofore traced the circuit of line-in d to the tip of said plug, and have also shown how the ground is taken off from wire d^5 when the lever e is thrown up to bring the telephone into circuit. I have not, 75 however, traced the circuit of the line-out—that is to say, the other limb or side of the metallic circuit of the calling subscriber. Beginning, then, at the sleeve f^{12} of the plug f , as shown inserted in the grounding spring-jack at board 1, I will trace the circuit of line-out as follows: From the sleeve f^{12} to the metallic socket or contact of the switch to line g , and thence to the contact-spring c^3 of the switch on the first board, and thence out to 80 line. It will be observed that line g is branched over to spring c^3 of the spring-jack switch of the line on board 2. I have thus shown how by a simple movement of the lever of the loop-switch of a line the operator brings her telephone into circuit and closes the test-wire of 85 the line to ground. I will now describe the test-wire and its connections in detail.

The test-wire h , it will be observed, is connected with the test-spring c^4 of each of the 90 spring-jack switches of the line on the different boards and also with the contact h' of the grounding spring-jack of the line. When cam-lever e is down in its normal position and no connection is made with the line at either 95 of the boards, the test-wire h is open. If when thus open a ground-wire, including a battery and telephone, be connected to one test piece or socket of the line, no current will pass through the telephone, and the operator 100 listening at the telephone and hearing no sound will know that the line is free—that is, not connected with any other line or in process of being connected. If, however, the test-wire be grounded at any other point when 105 the connection is made with a test-piece, the circuit will be completed and current will be sent through the telephone, and the operator 110 listening will know that the line is busy.

I have provided a ground-connection c^5 in 115 connection with each spring-jack, upon which the test-spring c^4 closes when the plug is inserted in any spring-jack switch. Thus in Fig. 4 test-spring c^4 is shown closed to ground-strip c^5 . This is a direct ground-connection, 120 and the test-wire when connected to show the busy test is not crossed or connected with the line. The operator then, having looped her telephone into a calling subscriber's metallic circuit and found out what other subscriber 125 is wanted, withdraws her plug f from the grounding spring-jack and proceeds to test the line of the subscriber called for.

At board 2, Fig. 9, the operator's plug i ,

which is the same as plug f at board 1, is shown withdrawn from the grounding-switch i' of its line. By touching the tip of plug f to the socket a' of the switch of any line it 5 may be determined whether the line is busy.

If the test-wire of the line tested is grounded, a circuit will be formed through the tip of the plug and strand f' to spring f^2 of the loop-switch, and thence, as before traced, 10 through the telephone f^6 and wire f^7 to the branch k , which is connected through test-battery k' and condenser k^2 to ground.

In case the line tested is found free, the operator will at once insert the plug f into the 15 switch, and by depressing one of the calling-keys f^8 or f^4 , as the case may be, sends current to line-wire m or n , as the case may be, these wires being preferably grounded normally at the subscriber's station. In case the 20 lines are simple metallic circuits, one of the keys f^8 f^4 might be dispensed with.

When plug f is inserted in the grounding-switch, as shown at board 1, the contact h' of test-wire h stands open. The hole through 25 spring d^3 is so large that no contact will be made between spring d^3 and contact h' . On removing the plug f from the grounding-switch spring d^3 takes a position between contact-spring d^4 and contact h' , thus allowing 30 spring d^4 to close upon the test-contact h' . Thus on throwing down the lever e the test-wire h is closed to ground by contact h' , spring d^4 , wire d^5 , and ground-contact d^6 . Thus when two lines are connected both of their 35 test-wires are connected to show the busy test, each to a different ground-connection—that is to say, the test-wire of the calling-line will be closed to a ground-connection d^6 and the test-wire of the called subscriber's line will 40 be closed to the ground-strip c^5 of the switch in which the plug f of the calling subscriber is inserted. Thus if plug f were inserted in 45 spring-jack switch 1 of metallic circuit m n , test-wire o of said circuit would be closed to ground-strip c^5 by test-spring c^4 of said switch 1. When thus connected, a test made at 50 switch p or q of either of the lines at any other board would indicate that the lines were busy. By means of a loop-plug r connected 55 with the operator's telephone, as shown more clearly at board 2, the operator may loop her telephone into circuit with the connected lines by inserting the said plug r into a spring-jack s , provided for this purpose.

At board 2 I have shown a key t for closing the test-battery to the telephone, since it would be preferable on some accounts not to have the test-circuit permanently connected with the operator's telephone.

In Fig. 10 I have shown a single circuit u , which is connected in the usual way through a different spring-jack switch on each of the multiple-boards and from the switch on the last board through a listening-in spring-jack, 65 and thence through the annunciator of the line to spring d^8 of the grounding spring-jack, and thence, as indicated, to spring u' of the

loop-key, and thence by strand u^2 of the flexible cord to the tip of the plug u^3 . This plug u^3 is shown inserted in a spring-jack u^4 of another line. The line connected with spring-jack u^4 may be either a single or a metallic circuit line. We may consider the spring-jack u^4 the same as the spring-jack p upon board 2, Fig. 9, and the connections may be 70 considered as the same. The plug u^3 being inserted in spring-jack u^4 , the line-terminal is separated from its normal contact and closes upon the tip of the plug, as shown, and the metallic sleeve of the plug, as shown more 80 clearly in Fig. 4, will be connected with the spring c^3 , through the medium of the metallic socket and the contact a^3 . The return portion of the metallic circuit is connected, as heretofore described, with a spring c^3 of each 85 of the spring-jacks upon the different boards of the line. The springs c^3 of the spring-jack switches of the line u , as shown in Fig. 10, are connected together by a wire v , which wire v , instead of returning to the subscriber's 90 station, is directly grounded. Thus it will be seen that any plug u^3 of a single-circuit line may be inserted, as shown, in spring-jack u^4 of a metallic circuit, to loop together the metallic circuit and the single-line circuit. The 95 loop-plug u^3 being inserted in spring-jack u^4 , loops the metallic circuit which may be connected with the spring-jack u^4 to the different terminals of the plug u^3 , and hence to the different strands of its flexible cord. 100

The strand which connects with the loop-plug u^3 is connected with the spring u^5 of the loop-switch. This spring u^5 , when in the position shown in Fig. 10, is connected with the wire v and the circuit may be traced through 105 this wire v to ground, as shown at v' . Thus when the circuit of the line u is connected with the metallic circuit the united circuit of the two lines may be traced from the ground at subscriber's station of the line u through 110 the spring-jack switch on each of the switch-boards, through the listening-in spring-jack and the individual annunciator, which now serves as clearing-out annunciator to the spring u' of the loop-switch, and thence 115 through a strand of the cord to the tip of the plug u^3 , and thence over the metallic circuit connected with the spring-jack u^4 back to the sleeve of the plug u^3 , and thence through said strand of the cord to spring u^5 , and thence to 120 wire v , and thence to ground.

The connection with the operator's telephone and the test-circuits and listening-in apparatus may be the same with single lines as heretofore described with respect to metallic circuits. Thus the test-wire w of the single circuit u is connected in the same manner as the test-wires h of the metallic circuit d g , shown in Fig. 9.

In Fig. 10 I have shown resistance t' in place 130 of condenser k^2 of Fig. 9. In the modification of the spring-jack shown in Fig. 11 the line-spring 1 normally rests upon its contact 2. The front portion 3 of the metallic socket is

insulated from the rear portion 4 thereof. The ground-contacts 5 correspond in function to the ground-contacts c^5 of the spring-jack shown in Fig. 4. The test-spring c^6 is normally in connection with the front or test portion 3 of the socket, as shown. If a plug be inserted, spring c^6 will be disconnected from portion 3 of the socket and closed upon ground-connection 5. The return portion of a metallic circuit may be connected with the rear portion 4 of the metallic socket, this rear portion being, for convenience, preferably extended to the rear for connection therewith, as shown. A spring-jack of the form shown in Fig. 11 might be made to occupy less space than any other form of spring-jack with which I am familiar having connections sufficient to do the work required.

In the modification shown in Figs. 12 and 20, instead of the metallic socket, I have shown a separate contact-piece 7, placed over the socket and permanently connected with the test-spring 6. The connection between the test-spring 6 and the test-plate 7 I preferably make through a hole bored through the switch-frame, as illustrated in Fig. 13.

My invention admits of many other modifications that will readily suggest themselves to those skilled in the art, and I therefore do not limit myself to the construction shown.

Having thus described my invention, I claim as new and desire to secure by Letters Patent—

1. A spring-jack switch consisting in the combination, with the tube, of two springs, which are interchangeably connected and disconnected therefrom upon the insertion and withdrawal of the plug, and the line-terminal spring and its normal contact, substantially as described.

2. The combination, with the tube or test-piece of a spring-jack switch, of the line-spring resting upon its contact and two springs on opposite sides of said line-spring, and insulating material on opposite sides of said line-spring, separating said line-spring from said other springs, respectively, and a loop-plug, which, on being inserted, separates the line-spring from its normal contact, at the same time permitting one of the two outer springs to fall away from its connection with the tube while the other outer spring is closed thereto, substantially as described.

3. The combination, with the tube a' , of the insulated springs c' , c^3 , and c^4 , the contact-point c^2 , against which spring c' normally rests, the loose pin between springs c' and c^4 , the ground-connection c^5 for spring c^4 , the spring c^3 being insulated from spring c' and adjusted to move therewith, and a plug which on being inserted separates spring c' from its normal contact and permits spring c^4 to separate from the tube and close upon its ground-contact c^5 , while at the same time spring c^3 is forced into connection with said tube.

4. A strip of spring-jacks, each consisting of a socket with which two different springs

are alternately connected and disconnected on the insertion of a plug, the portion of the strip containing said sockets being removable, substantially as described.

5. The socket a' , provided with contact-points a^2 and a^3 , said contacts being extended to inclose springs on opposite sides of a spring-jack, in combination with said springs, and means for alternately connecting and disconnecting said springs from said contacts.

6. A spring-jack switch provided with a line-terminal, the normal contact of said line-terminal, a test-spring insulated from said line-terminal, and a connection for the return portion of a circuit, in combination with the loop-plug inserted in said switch, whereby the line-spring is separated from its normal contact and closed to the tip of the plug, while at the same time the return-connection of the switch is closed to the sleeve of the plug.

7. A ground spring-jack switch consisting of the lever d^8 , permanently insulated from the connection h' of said switch, a ground-connection d^4 , and the insulated socket or frame, in combination with a loop-plug, which on being inserted separates ground-connection d^4 from connection h' and closes connection d^3 to said ground-connection d^4 while connection is made between the tip of the plug and spring d^3 , and at the same time the sleeve of the loop-plug connected with the socket, substantially as described.

8. The loop-plug f and its terminals connected with springs f^2 f^{10} , respectively, said springs including in their circuit a telephone and a branch ground-connection k , including a test-battery, substantially as described.

9. Two metallic-circuit telephone-lines, each connected through different spring-jack switches on two or more multiple switch-boards and each provided with a loop-plug terminal and test-circuits, one for each line, each of said test-circuits being normally open, in combination with independent ground-connections for each of said test-circuits, with which ground-connections said test-circuits are closed automatically on the insertion of the loop-plug terminal of one line into a spring-jack switch of the other line.

10. A telephone-line connected through the line-terminal and contact of two or more switches on different switch-boards and thence through an annunciator, and thence normally through a grounding-switch to ground, in combination with a return-wire connected with a spring of each of the spring-jack switches of said line, and with the grounding-switch, an independent test-wire for said line connected with another spring of each of the spring-jack switches of the line and with a contact of the grounding-switch, and direct ground-connections, one for the test-wire spring of each of the spring-jack switches and one for the grounding-switch, whereby a signal may be sent over the line to throw down the annunciator and a test-circuit provided, the circuit

of which is provided with a direct ground-connection when the telephone-line is connected with another line.

11. The combination, with two telephone-lines connected together, of separate local test-wires, one for each of said lines, said telephone-lines being each connected with spring-jack switches on different multiple switch-boards, and the test-wires being connected with each of the spring-jack switches of their lines, respectively, and a direct ground-connection ^{c⁵} for each of the spring-jack switches, whereby each of said test-wires is provided with a different direct ground-connection independent of any portion of said telephone-lines when the two lines are connected, substantially as described.
12. In a multiple-switch-board system, a test-wire normally connected with a test-piece of each of the switches of a telephone-line, in combination with a special direct ground-contact on each of the spring-jack switches, whereby on making connection with said line at either switch said test-wire is disconnected from said test-piece and closed to the special direct ground-contact of the spring-jack switch at which the connection is made.

13. In a multiple-switch-board system of telephone-exchange, two telephone-line circuits provided with spring-jack switches, a ³⁰ separate spring-jack switch being provided for each line on each board, in combination with the test-circuits, a separate test-circuit being provided for each telephone-line, the test-circuit of each line being connected with a special test piece or spring of each of the switches of its line and a direct ground-connection near each special test-connection, said direct ground-connections being independent of any portion of the telephone-lines, and ⁴⁰ plugs at the different switch-boards, whereby on inserting a plug in any switch the special test-connection of the switch will be closed directly to ground without closing or connecting the test-wire with the main-circuit line. ⁴⁵

In witness whereof I hereunto subscribe my name this 23d day of November, A. D. 1887.

FRANKLIN G. BEACH.
